UNITED STATES PATENT OFFICE.

HERMAN WITTIG, JR., OF NORTH PHILADELPHIA, PENNSYLVANIA.

AUTOMATIC PLAYER-PIANO.

1,176,877.

Specification of Letters Patent. Patented Mar. 28, 1916.

Application filed November 23, 1914. Serial No. 873,532.

To all whom it may concern:

Be it known that I, HERMAN WITTIG, Jr., a citizen of the United States of America, residing at North Philadelphia, in the 5 county of Philadelphia and State of Pennsylvania, have invented certain new and useful Improvements in Automatic Player-Pianos, of which the following is a specification.

10 The present invention relates to improvements in automatic player pianos, and involves especially the improvements in the pneumatic valves and the striking devices used in connection therewith.

15 The invention involves the double system of valves, in which the striking pneumatics are controlled by means of a secondary valve, which is in turn controlled by a primary valve actuated from the tracker board.

20 The primary object of the invention is to provide a pneumatic striking device in which the actuating parts are closely assembled in order to require a minimum travel of air as the device is actuated, and 25 also in order to provide a device which is compact and comparatively small in compass so that it will occupy comparatively small space within the piano, and well adapted to use in connection with all standard 30 pianos.

A further object of the invention is to reduce the cost of production and the cost of maintenance of the pneumatic actuating device, and further to provide an adjustable 35 flexible striking device to take up lost motion and used in connection with the piano action that will produce a result closely approximating the human touch upon the piano keys.

40 With these and other objects in view, the invention consists in certain novel combinations and arrangements of pneumatic valves and flexible striking devices, as will be hereinafter more fully described and 45 claimed.

In the accompanying drawings I have illustrated one complete example, and a slight modification thereof, of a complete embodiment of my invention constructed 50 according to the best modes I have so far devised for the practical application of the principles of the invention.

Figure 1 is a sectional view showing the primary and secondary valves and the striking device illustrated in connection with a portion of the piano action. Fig. 2 is a view

of one of the valve boxes and its valve slightly modified from the construction shown in Fig. 1. Fig. 3 is an enlarged detail sectional view showing one of the features of the flexible striking device. Fig. 4 is a fragmentary sectional detail view showing a flexible joint between the piano action and a rocker arm of the striking device. Fig. 5 is another detail sectional view showing a screw for regulating the rocking movement of the rocker arm of the striking device with relation to the piano action. Fig. 6 is a side elevation of one of my improved rocker arms. Fig. 7 is a perspective view of 70 a fulcrum block, one of which is required for each striking device.

In the preferred embodiment of my invention, as illustrated in the drawings, I have shown the usual piano key 1, with its 75 adjustable abstract lifting device 2, and the piano abstract 3 to which is attached the cushioned lifter 4, all as ordinarily used in the standard piano action. In the drawings I have illustrated only one action and its 80 connection with the action of the piano, and it will be understood, of course, that as many of these devices will be employed as are required, usually sixty-five or eighty-eight.

In utilizing my device, I employ the valve box 5, to which is attached the rubber hose or suction tube 6, extending from the tracker board as usual to the valve box, and this suction hose opens into a channel 7 in the valve box 5. This channel 7 extends horizontally along the bottom of the box, and has at its end a vertical passage 8, above which is located the diaphragm 9 of the suction chamber 10, the diaphragm shutting off communication between the passage 8 and the suction chamber, as clearly shown. Within the suction chamber the primary 90 valve 11 is located, its stem 12 extending up through the vertical passage 13, the upper port of which passage being closed by the valve 15. It will be seen that the port 15 opens to the atmosphere at the top of the valve box 5. An additional channel 16 extends horizontally from the passage 13, and opens at one side of the diaphragm 17 in the vacuum chamber 18. The number 18' in Fig. 1 indicates an opening (dotted lines) 95 from vacuum chamber 18 to an exhaust chest (not shown) to accomplish the pneumatic result. This chamber is located in the valve box 19, and the secondary valve 20 is adapted to be actuated from the diaphragm

100 105 110 115

17. This valve 20 has a stem 21, which at its outer end is supported in a guide piece 22 attached to a strip 23. This strip 23 is detachable, and extends the whole length of the pneumatic action, being provided with perforations 24, and one of the brackets 22 is provided for each of the stems 21. Thus, if it is desired to gain access to any of the valves, the removal of the strip 23 is all that is required, and all the valves are then accessible. The stem 21 carries two cut-off valves as 25 and 26, the former being the vacuum valve, and the latter the atmosphere valve. The vacuum valve 25 is adapted to seat upon an open disk 27, and the atmosphere valve or cut-off is adapted to seat against the walls of the port or opening 24.

10 The valve chamber 28 in which the two valves 25 and 26 operate, is in communication through a channel 29 with the pneumatic 30 of the pneumatic action. The upper or top board 31 of the pneumatic is perforated as shown, and it is attached to the under side of the secondary valve box, and 15 the bottom board 32 is of usual construction.

10 In operation the movement of the primary and secondary valves is simple, quick, and positive. Assuming an air impulse 30 coming from the tracker board as the perforated paper travels over the board, the air rushes through the suction tube 6 and through the channel 7 and passage 8. As 35 the pressure from the passage 8 impinges against the diaphragm 9, the diaphragm 9 contacts with the primary valve 11, and lifts the valve head 15 from its port 14, and closes the lower end of the passage 13. The air now passes through port 14 and channel 16, and the pressure of air against the diaphragm 17 moves the secondary valve to the right, closing the port 24 from the atmosphere, and opening port 27 to the vacuum chamber 18. The air in the pneumatic 30 now rushes up through the channel 29 into the valve chamber and vacuum chamber, and the pneumatic is collapsed, the bottom board 32 of course swinging upwardly at the right in Fig. 1. This collapse of the bellows and movement of its 40 perforated note sheet actuate the striking mechanism, and this mechanism is constructed as follows: A rail 33 extends longitudinally of the piano and is located below the bellows 30. Attached to this rail are a suitable number of fulcrum blocks 34. A screw 35 is illustrated for attaching the block to the rail, and the lower end of each block is bifurcated, and provided with forked 45 ends 36. These forked ends are designed to provide a fulcrum for one of the striking members 37, a pin 38 extending through the forked ends and the striking member 37 to form a fulcrum for said member. The 50 striking member is connected to the bottom

board 32 of the pneumatic by means of a striker rod 39 and a bracket 40, the latter being attached to the under side of the bottom board, and the former being connected at its ends to said bracket and the striking member. An additional or auxiliary member is used in connection with each striking member, and this member is a rocker arm 41, as clearly illustrated in Figs. 1 and 6. This arm has a fulcrum point 42 which rests 55 upon the upper side of the striking member 37, and as clearly seen in Figs. 1 and 3, it is guided between the forked ends 36 of the fulcrum block. The rocker arm is slightly longer than the striking member, and at its right end projects beyond the striking member and is formed with a head 42' in contact with the lifter 4, on the piano abstract 3. At its other end the rocker arm projects beyond the striking member, and is provided with the usual touch button 44. These two members, the striking member and the rocker arm, are thus adjustably connected together so that the head 42' may be maintained in contact with the lifter 4 at all 60 times, and should these members become separated for any reason the head 42' may be brought back to the lifter by adjusting the screw 45. In this manner lost motion is prevented between the lifter and the head. 65

In Fig. 5, it will be seen that this screw is threaded into the striking member 37 of the piano action, but the screw loosely engages the rocker arm, because of the presence of a slot 46 in the arm. A washer or 70 head 47 is used on the screw, and it will be readily seen that the rocker arm is limited in its movement away from the striking member. At the other side of the fulcrum point 42, the rocker arm is cushioned with relation to the striking member, by means of a screw 48 which is threaded into the striking member 37, and passes through a perforation in the rocker arm. A spring 50 is located 75 between the washer 51 and the upper side of the rocker arm, and it will readily be seen that the function of this spring is to cushion the movement of the right end of the rocker arm when the screw 45 is turned to depress the left end of the rocker arm. 80

The operation of the striking device will be readily understood. As the pneumatic 30 collapses, it lifts the right end of the striking member 37 through the connecting rod 39, and instead of imparting a direct blow to the lifter on the abstract 3, the rocker arm due to the natural pliability of the wood of which the striking member and rocker arm are composed, absorbs the sudden or quick shock of the movement of the pneumatic, and the shock or jerk of the movement of the striking action is dispelled so that the head 42' lifts the piano abstract 3 with a movement closely approximating the touch of human hands. 85

The two screws 45 and 48, in addition to performing the before mentioned functions also prevent lateral movement of the rocker arm with relation to the striking member, and the parts are so arranged that there is practically no lost motion whatever, no sudden shocks or jars to the parts, and this smoothness of movement and action not only renders the player action more durable, but 10 also preserves the piano action itself. It will be readily seen that the movement of the rocker arm may be adjusted with relation to the striking member, by turning the screws 45 and 48, and this feature permits 15 adjustment of the player parts, and each striking member may be adjusted independently of the others.

In the modified form shown in Fig. 2, the valve box 5' is provided with a suction pipe 20 or rubber tube 6' which enters the single channel 7 in a horizontal position, instead of in a vertical position as shown in Fig. 1. This form of the invention is preferable in some cases, and is adapted for use in certain 25 arrangements of the player action.

What I claim is:

1. The combination in an automatic piano

player with a striking device comprising a pivoted arm, a pneumatic and a connection between said arm and pneumatic, of a bodily 30 movable, separate rocker arm fulcrumed on the pivoted arm and adapted to engage an abstract in the piano action, and an adjustable connection for said rocker arm to hold it in contact with the abstract.

2. The combination in a striking device including a pivoted member, a pneumatic, and a connection between the pivoted member and pneumatic, of a bodily movable, 40 separate rocker arm fulcrumed on said member and having a perforation near one end, an adjusting screw passed through said perforation and threaded in the pivoted member, and an adjusting screw at the other side of said fulcrum, and a spring between said screw and the rocker arm, whereby the rocker arm is held in continuous contact 45 with a portion of the abstract.

In testimony whereof I affix my signature in presence of two witnesses.

HERMAN WITTIG, JR.
